TUBE COVERING

Harrison E. Kleffel, New York, N. Y.

Application March 27, 1931, Serial No. 525,682

12 Claims. (Cl. 137—100)

This invention relates to improvements in tubes for use in the furnace chambers of boilers, oil stills and other apparatus of that sort for the purpose of breaking up stratification of and producing turbulence in the stream of burning gases so as to promote combustion. More particularly, the invention is concerned with protected or covered tubes which are provided with a covering around their total circumference and throughout such lengths thereof as are to be exposed directly to the furnace temperature, the covering being selected to control the rate of heat transfer through the tube walls to the contents of the tubes and also acting to reflect heat back into the furnace cavity to further promote combustion.

In my co-pending application, Serial No. 439,-349, filed March 27, 1930, now United States Patent No. 1,884,741, issued October 25, 1932, I have set forth and claimed apparatus of the type described in which covered tubes are disposed in the furnace cavity of a boiler furnace, oil still, etc. in the region where combustion is taking place and serving the purpose above referred to, and have also described and claimed certain forms of covered tubes. The tubes disclosed in the present application constitute further modifications of and improvements upon those set forth in the prior application but involve the same principles of construction and operation.

In the prior application, the tubes disclosed are provided with coverings constructed either with a refractory or a metallic outer surface. In both instances, the coverings are firmly anchored to the tube and in effect constitute an integral part thereof. In the first construction, the tube is provided with a metallic sleeve shrunk on the tube and having means by which the refractory may be held thereon, such as dove tail connections. In the second construction, the tube is first covered with refractory material which is held in place by an outer sleeve of metal.

Such tube coverings are not to be confused with refractory tile sleeves, either cylindrical or semi-cylindrical, which have heretofore been used to some extent in boiler installations. A single row of tubes with such sleeves have been employed for the furnace walls or in some instances tubes with sleeves extending part of their length have been placed in the path of the furnace gases. When such refractory sleeves are mounted on tubes, an intimate contact between the covering and the tube cannot be obtained because the inherent mechanical weakness of the refractory prevents the latter from being tightly

clamped in place. The refractory and tube expand at different rates and this causes an air gap between the refractory and tube which reduces the rate of heat transfer and frequently results in the destruction of the refractory when subjected to furnace temperatures, or, if the refractory is tightly clamped to the tube, the difference in temperature causes the refractory to be cracked.

In my present tubes, the tube covering is placed in position under such conditions as to produce an intimate contact between the tube and covering at all times and this result is obtained without the liability of cracking or spawling the refractory when it is exposed to operating conditions.

My form of tube covering also has the additional advantages in that the metallic sleeve provides added strength to the tube against bending and bursting, helps to distribute the heat more uniformly over the tube surface and also provides a protective covering for the tube itself against the oxidation and erosive action of the flame.

For a better understanding of the invention, reference may be had to the accompanying drawings in which

Fig. 1 is a transverse view of one type of the new tubing;

Fig. 2 is a side elevation of the tube illustrated in Fig. 1, with certain parts broken away and shown in section;

Fig. 3 is a transverse sectional view of a modified construction;

Fig. 4 is a transverse section of a special tube in which the tube and a part of the covering are made integral;

Fig. 5 is a sectional view of a modified form of the tube shown in Fig. 4;

Fig. 6 is a transverse sectional view of another tube;

Fig. 7 is a longitudinal sectional view of the construction shown in Fig. 6;

Fig. 8 is a sectional view on the line 8—8 of Fig. 9 of a modified construction in which air spaces are used as an insulator between the tube and its outer covering layer;

Fig. 9 is a longitudinal sectional view of the construction shown in Fig. 8, the tube being shown in elevation;

Fig. 10 is a fragmentary sectional view showing a modification of the construction illustrated in Fig. 8;

Figs. 11 and 12 are transverse and longitudinal sections of a modified form of the construction shown in Fig. 8;

Fig. 13 is a transverse section of a modification of the construction illustrated in Figs. 1 and 3,

Fig. 14 is a view in side elevation with parts shown in section of the construction illustrated in Fig. 13; and

Figures 15 to 19, inclusive, are views corresponding to Figures 8 to 12, inclusive, but illustrating a modified construction.

Referring now to the drawings, there is illustrated in Figs. 1 and 2 a conventional tube 20 provided with a covering which comprises a metal sleeve 21 in intimate contact with the outer surface of the tube and provided with lengthwise dove tail grooves 22 and projections 23 between the grooves. Mounted on the sleeve are insulating or refractory segments 24, these segments being anchored in the grooves and separated by expansion material 25 providing longitudinal joints between the sides of adjacent segments 20 and similar joints between the ends thereof as indicated at 26. If desired, the metallic sleeve 21 may be made up of a plurality of sections having stepped ends as illustrated at 27, these ends serving to take up expansion in the sleeve.

In constructing the tube, the metal sleeve is heated and the sleeve shrunk in place. The refractory segments are preferably placed in position on the sleeve while the latter is heated so that when the sleeve cools off and shrinks it grips the tube tightly and also grips the tongues 28 of the refractory which lie in the dove tail grooves of the sleeve. Intimate contact of the refractory with the metal sleeve is thus obtained as well as intimate contact between the metal sleeve and the tube and since the sleeve and tube have the same co-efficient of expansion they lie in close contact throughout during operation. During operation, the refractory material and the metal projections on the sleeve expand at a slightly greater rate than the tube and that part of the sleeve which is in intimate contact with the tube and kept relatively cool by heat transfer to the contents of the tube. Consequently as the refractory expands due to an increase in temperature, it is held more firmly in the dove tail grooves.

Instead of employing a complete refractory covering over the metallic sleeve as illustrated in Figs. 1 and 2, I may use the construction illustrated in Fig. 3 in which the tube 20 is provided with a sleeve 21 having dove tail grooves and projections as before. In the grooves is placed refractory or insulating material 29, this material projecting slightly beyond or terminating flush with the surface of the sleeve but not covering the tops 55 of the projections thereon. The refractory material may be in suitable lengths or sections, provided at their ends with expansion joints as illustrated in Fig. 2.

Instead of employing a separate metallic sleeve for the purpose of anchoring the refractory, I may produce a special tube illustrated in Fig. 4 in which the tube and sleeve are formed integral. Such a tube 30 may be made by extrusion or drawing and is provided with dove tail grooves 31 and integral projections 32 similar to those ordinarily formed on the sleeve. In the grooves are placed sections 33 of refractory or insulating material which are flush with or project outwardly beyond the face of the tube but do not cover the tops of the integral projections thereon. In Fig. 5, there is shown a modified form of the construction illustrated in Fig. 4, in which the tube 30 is provided with grooves and projections with segments 34 of insulating or refractory material anchored in the grooves and covering the tops of the projections.

These blocks of refractory or insulating material may be separated by expansion material 26, as in the construction illustrated in Fig. 2. In the tube shown in Fig. 5, the entire outer surface of the tube is covered by insulating or refractory material.

In some instances, it may be desirable to provide the tube with an outer metallic covering so constructed that the rate of heat transfer through the tube can be controlled. For this purpose, the construction illustrated in Figs. 6 and 7 may be employed, if desired. In these arrangements, the tube 20 is provided with an outer metallic sleeve 35 which, if desired, may be made in short lengths 35^a and 35^b, for instance, Fig. 7. Between the metal sleeve and the tube is placed insulating or refractory material 36 by which the rate of heat transfer to the tube may be regulated and controlled. The sections of the sleeve may, if desired, be provided with inwardly extending flanges 37 and between adjacent sections is placed expansion material 26, this expansion material also separating the ends of adjacent portions of the insulating material.

In the construction shown in Figs. 8 and 9, the tube 20 is provided with the outer metallic sleeve 35 spaced from the tube and forming a plurality of air chambers 38 which act as insulators. In the construction shown in these figures, the metal sleeve 35 is made up of short sections having stepped joints 39 at their ends, each section being provided with an integral circumferential flange 40 which contacts intimately with the surface of the tube. With this arrangement, heat absorbed by the covering is transmitted to the tube 100 through the flanges by conduction and through the spaces between the flanges by radiation, this radiated heat increasing to a maximum when the covering becomes incandescent.

In Fig. 10 there is illustrated a modified form 105 of construction similar to that shown in Figs. 8 and 9. Here, the sleeve 35 is provided with longitudinal fins 41 which increase the heat-absorbing surface of the sleeve.

In Figs. 11 and 12, there is illustrated a modification of the construction shown in Figs. 8 and 9. In the modified arrangement, the tube 20 is enclosed within a sleeve 42 which, if desired, may be made up of short lengths 43 with stepped joints 44, the sections being provided with longitudinal 125 internal flanges 45 instead of the circumferential flanges 40 shown in Figs. 8 and 9. Between the longitudinal flanges on the sleeve are air chambers 46 which serve as insulators.

In the construction where air serves as an insulator between the tube and covering I may substitute where necessary an insulating or refractory material. Constructions in which solid material replaces air as an insulator are shown in Figures 15 to 19, inclusive.

In Figs. 13 and 14, there is disclosed still another modification in which the outer surface of the covered tube is composed in part of refractory and in part of metal. Mounted on the tube 20 in intimate contact therewith is a sleeve 47 140 which is provided with a plurality of undercut openings 48 in which refractory material is carried. The number, shape, size and arrangement of these perforations in the sleeve may be varied in accordance with the purpose to which the tube 145 is to be put. The refractory material is held in place by the overhanging walls of the openings in the sleeve and maintained in intimate contact with the tube at all times.

It will be observed that in all of the construc-

tions illustrated, the tube covering is in intimate contact with the surface of the tube and the tube is thus covered around its total circumference with a covering which may be varied as to 5 material, thickness, and arrangement so as to control the rate of heat transfer to the contents of the tube. With these tubes, it is possible to maintain a hot or incandescent surface which promotes combustion, while the circulation of the 10 contents of the tube limit the temperature to which the covering is raised during service. The refractory or insulating material or the air spaces in the covering are of lower heat conductivity than the metal part of the tube covering 15 and the metal sleeves serve to hold the refractory or insulating material or to define air spaces around the circumference of the tube, as well as providing a path for the travel of heat to the exterior surface of the tube. In addition 20 they serve to strengthen and protect the tube.

In the furnace practice, these tubes may be employed in the furnace chamber and in the region where combustion is taking place for the purpose of producing turbulence in and breaking 25 up stratification of the gases, with resultant improved and more rapid combustion. In oil still practice in which bare tubes are exposed to the furnace heat in the still, such tubes are subject to overheating and bursting due to carbonization of the oil on the interior of the tubes 30 in local areas, which causes overheating of the tube. With the present covered tube, the rate of heat transfer to the tube contents is controlled, the heat more uniformly distributed 35 around the tube and the tube strengthened against bursting so that the still can be operated at higher temperatures and with greater efficiency.

In the drawings, I have shown varying arrangements of the metal sleeve and of the refractory or insulating material. It is to be understood that the arrangement and thickness of the sleeve and the kind, arrangement, and thickness of the refractory or insulating material 40 may be varied as desired, and it may be applied in molded or plastic form.

I claim:

1. A tube structure which comprises a tube, a metallic covering over the tube and spaced therefrom throughout the greater portion of its extent, said covering having a multiplicity of extensions from its inner surface and disposed along its length, said extensions contacting with the outer surface of said tube and non-metallic material between the covering and the tube and 50 in intimate contact therewith.

2. A tube structure, which comprises a tube, a metallic covering over the tube and spaced therefrom throughout the greater portion of its extent, said covering having a plurality of extensions from its inner surface toward the outer surface of said tube and being made up of a plurality of cylindrical sections disposed from end to end along the tube, and non-metallic material between the covering and the tube and 60 in intimate contact therewith.

3. A tube structure, which comprises a tube, a metallic covering over the tube and spaced therefrom, said covering having a plurality of extensions from its inner surface toward the outer surface of said tube and being made up of a plurality of cylindrical sections disposed along 70

the tube from end to end and having expansion joints between the ends of adjacent sections, and insulating material between the covering and tube and in intimate contact therewith.

4. A tube structure which comprises a tube, a metallic covering over the tube having a multiplicity of extensions from its inner surface toward the outer surface of the tube, said extensions being disposed along the inner surface of said covering from end to end of the latter and insulating material between the tube and covering and in intimate contact therewith. 80

5. A tube structure, which comprises a tube, a metallic covering over the tube and spaced therefrom, said covering having a multiplicity of extensions from its inner surface and spaced along the length thereof, said extensions contacting with the outer surface of the tube, and insulating material between the tube and covering and in intimate contact therewith. 85

6. A tube structure, which comprises a tube, a metallic covering over the tube having a multiplicity of spaced portions along its length in direct contact with the tube, and insulating material held in position by said covering, said 90 material having portions in contact with said tube and with said covering.

7. A tube structure which comprises a tube, a metallic sleeve enclosing the tube and having a multiplicity of spaced portions along its length in intimate contact therewith, and masses 105 of refractory material held in place by said covering, said masses being in intimate contact with said tube and with said covering.

8. A tube structure, which comprises a tube, a metallic covering for the tube, and non-metallic material between the tube and covering and in intimate contact therewith, said non-metallic material being in the form of arcuate portions 110 with material between adjacent portions permitting expansion thereof. 115

9. A tube structure, which comprises a tube, a metallic covering therefor, and refractory material held in place by said metallic covering, said refractory material being made up of a 120 plurality of arcuate blocks with material between the ends and sides of adjacent blocks permitting expansion thereof.

10. A tube structure, which comprises a tube, a metal covering for the tube, and refractory material held in place by said covering, said material being in the form of arcuate blocks 125 with material between said blocks permitting expansion thereof.

11. A tube structure, which comprises a tube and a smooth bare metallic covering therefor 130 having portions spaced from the tube and providing chambers between the covering and tube, said covering having projecting flanges in its inner surface extending circumferentially of the tube, said extensions in part defining said chambers.

12. A tube structure, which comprises a tube, and a metallic covering therefor, this covering being made up of a plurality of cylindrical sections disposed in end to end alignment with 140 expansion joints between the ends of said sections, said sections having portions spaced from the tubes to define chambers between the covering and tube and other portions extending inwardly from its inner surface along its length 145 and in part defining said chambers.

HARRISON E. KLEFFEL.
